(57) **CLAIM**

The ornamental design for a double wall vacuum insulated bottle, as shown and described.

DESCRIPTION

FIG. 1 is a perspective view of a double wall vacuum insulated bottle showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1; and,

FIG. 7 is a bottom plan view of FIG. 1.

The stippling shown in the drawings is indicative of a colored surface portion of the double wall vacuum insulated bottle. Further, the oblique surface lines in the drawings represent a metallic surface portion of the double wall vacuum insulated bottle.

The dash-dot broken lines in the drawings depict portions of the double wall vacuum insulated bottle that form no part of the claimed design. The dash-dot broken lines shown in the drawings depict boundaries of the claim that form no part of the claimed design.
